Cooper, Kerr & Dunham

UNITED STATES PATENT OFFICE.

LE GRAND C. BUSH, OF PHILADELPHIA, PENNSYLVANIA, ASSIGNOR TO INTERNATIONAL TIME RECORDING COMPANY OF NEW YORK, OF ENDICOTT, NEW YORK, A CORPORATION OF NEW YORK.

INTERLOCKING DEVICE FOR DOORLOCKS AND THE LIKE.

Original application filed August 9, 1924, Serial No. 731,006. Divided and this application filed March 2, 1925. Serial No. 12,504.

The present application is a division of my copending application, Serial No. 731,006, filed August 9, 1924.

The present invention has for its objects the provision of improvements in the interlocking devices for preventing the operations of the main lock or bolt when supplementary locks or bolts disposed on windows or doors at remote points are in unbolted or unlocked condition. These interlocking door systems are claimed broadly in my former Patent No. 1,270,264. The present construction is directed to an improvement in my former construction making the same reliable by introducing additional advantages not heretofore obtained.

The interlocking arrangement of the present invention is such that a broken wire, an exhausted battery, or poor contact will not prevent the locking of the main door, and accordingly the interlocking circuit is provided with supplementary lock-control contacts, which are normally closed when the supplementary bolts are withdrawn.

In previous constructions, the arrangement of the interlocking circuit was such that the supplementary bolt contacts were normally open with the bolt withdrawn and closed upon the advancement of the supplementary bolts. Provision is also made in the interlocking circuit for only effecting final closure and completion of the circuit by and upon the manipulation of the main lock. In this way the consumption of the battery current is minimized.

A further object of the present invention resides in the provision of a recording mechanism, operating devices therefor, and a bolt structure wherein the locking bolt may be readily reversed for left or right hand operation without the necessity of making extensive changes or modifications in the recording devices.

Further objects and advantages will be hereinafter pointed out in more detail in the accompanying specification and claims and shown in the drawings, which, by way of exemplification, show a preferred embodiment of my invention.

In the drawings,

Fig 1 is a detail view of the interlocking

mechanism showing these parts in moved position.

Fig. 2 is a part sectional view of the key barrel mechanism and associated operating parts.

Fig. 3 is a circuit diagram of the apparatus showing the interlocking circuit extending to a plurality of supplementary locks.

In the present application the details of the recording lock feature per se are not illustrated as these form the subject matter of my parent application above referred to. The bolt and lock mechanism is of conventional type including a tumbler barrel 20 (Fig. 2) with provisions for receiving Yale lock keys 21. Slidably fitted in the barrel 20 but fixed against rotation therewith is a key 22 which in operation is fixedly secured in a combination bolt actuating barrel and key bolt selecting device 23. Barrel 23 is slotted as shown at 26 and has keyed to it a member 27 having a lug 28 adapted to engage the notch in the locking bolt 30. It will be understood that the unlocking operation is effected by turning the parts shown in Fig. 1 by means of the key and bolt barrel in a clockwise direction and that locking may be effected by turning the key and the parts controlled thereby reversely.

Provision is made with the present device for preventing the locking of the door in the event that one or more windows or other doors or locks which may be disposed at points remote from the main lock are unlocked. For this purpose member 27 is provided with a locking ratchet disk 92 carrying shoulders or teeth 93 (see Fig. 1). Arranged to cooperate with these teeth but normally out of cooperation therewith there is an interlocking pawl 94 which is suitably connected to an armature of an interlocking magnet 95. Upon the energization of this magnet (see Fig. 1) the pawl 94 will be rocked into such position that it will be adapted to engage the teeth 93 and thereby prevent the complete rotation of member 27. Otherwise stated, said interlocking device permits a partial rotation of the member 27 but prevents such extent of rotation as is necessary to advance the bolt 30. The

initial rotation of member 27 is utilized for effecting the closure of a pair of contacts 96 which are in circuit with the interlocking means to thereby supply the magnet with energy only upon actuation of the bolt actuating member 27. In this way the current is utilized only at such times when there is an attempted manipulation of the bolt. For effecting closure of the contacts 96 a cam member 97 is provided on member 27, which actuates the pivoted contact actuating lever 98. The contacts 96 normally remain open due to their own resiliency. In Fig. 1 these contacts are shown closed by the action of cam 97 on member 98.

It will be understood that the interlocking devices do not prevent unlocking operations of the door. Referring to Fig. 1, if the part 92 be turned in a clockwise direction, which is the direction of rotation for unlocking, member 94 would ride up upon the slope of the interlocking abutment 93 and would not affect any arresting of the member 92 and the parts connected therewith.

Referring now to the circuit diagram, 99 designates a suitable source of current. Contacts 100 and magnet 40 require no description as these relate to the time recording mechanism of the lock. The interlocking circuit 101 includes a plurality of contacts 102 normally biased to open position and adapted to be closed when the bolts or locks of the remote doors or windows are in retracted or open position. These contacts upon the supplementary locks are in multiple in circuit 101 and, consequently, if any of the remote supplementary locks are open or unlocked, current may flow through 101 to the normally opened interlocking contacts 96; then upon the attempted locking of the main door, these contacts will be closed permitting the interlocking magnet 95 to be energized and thereby preventing the locking of the main door. If all of the contacts 102 are opened showing that all of the remote supplementary locks are locked, the interlocking circuit 101 will be opened and then irrespective of the closure of contacts 96, the interlocking magnet 95 will not be energized and there will be no preventing of the locking of the main door when such operation is attempted.

The contact and circuit arrangement is such that if the battery or source of current 99 is ineffective, for example, if weak or exhausted, the main door may be locked, since the interlocking circuit does not receive sufficient current to energize the interlocking magnet to attract its armature and displace pawl 94. The main lock also can be advanced if there is a broken wire in the system inasmuch as the interlocking circuit will then be interrupted and no current can flow through the interlocking magnet. If the contacts 102 are out of adjustment or

if the contacts are dirty the system will so function that the main lock cannot be locked. By reason of the fact that the interlocking circuit is normally kept open by the contacts 96 the current consumed for the interlocking functions is very low inasmuch as no current is consumed except at the times when the main door is being locked or unlocked.

What I claim is:

1. In an interlocking door system in combination with a main door lock and one or more supplementary locks, an interlocking means at the main door lock for preventing the locking thereof whenever the supplementary locks are unlocked, said means including an interlocking circuit extending from the main to the supplementary locks, said means being ineffective to prevent the locking of the main door upon accidental breaking of the interlocking circuit.

2. In an interlocking door system in combination with a main door lock and interlocking means for preventing the locking of the same including an interlocking circuit extending from the main lock to one or more supplementary locks, means operative when the supplementary locks are unlocked for preventing the locking of the main door, said means being ineffective to prevent locking of the main door upon accidental breaking of the interlocking circuit.

3. In an interlocking door system, a main door lock, one or more supplementary locks, interlocking means for said main door lock to prevent locking operation thereof, means for controlling said interlocking, means comprising an interlocking circuit extending to said one or more supplementary locks, circuit controlling means disposed at said supplementary locks, said last means being adapted to be closed at all times when said supplementary locks are unlocked, and said closure of the interlocking circuit preventing the locking of the main door.

4. An interlocking door system comprising a main door lock, an interlocking means therefor, for preventing the locking of the main door lock, an interlocking circuit extending to one or more supplementary locks, contacts therein operated by said supplementary locks, contacts being normally closed when said locks are unlocked, means operative upon the closing of any of said contacts at any lock for establishing circuit conditions in the interlocking which will subsequently prevent the locking of the main door.

5. An interlocking door lock system for preventing the locking of a main door when one or more supplementary locks are unlocked, comprising in combination, an interlocking magnet, an interlocking circuit including said magnet and extending to and controlled by the supplementary locks, and circuit controlling devices at said supplement-

5 tary locks and disposed in the stile in said interlocking circuit adapted upon closure by said supplementary locks being unlocked to subsequently establish an interlock condition for the main door lock.

6. An interlocking door lock system for preventing the locking of a main lock when one or more supplementary locks are unlocked, including in combination an interlocking circuit controlled in part by the supplementary locks, and means operative upon the locking of the main lock for completing the establishing of said interlocking circuit.

10 7. An interlocking door lock system for preventing the locking of a main lock when one or more supplementary locks are unlocked, including in combination an interlocking circuit, and means for controlling

the same to establish an interlocking condition for the main lock conjointly in accordance with the locked or unlocked condition of the supplementary locks and by and upon the attempted locking of the main lock.

8. An interlocking door lock system for preventing the locking of a main lock when one or more supplementary locks are unlocked, comprising in combination with an interlocking circuit, means for controlling said circuit to partially establish the same upon the unlocking of any one of the supplementary locks, and means for completing the establishment of said circuit.

15 In testimony whereof I hereto affix my signature.

LE GRAND C. BUSH.
